STABILIZING MEANS FOR RELAY TYPE
REGULATORSJames L. Kimball, Danvers, Mass., assignor to
Ruggles-Klingemann Mfg. Co., Salem, Mass.

Application August 7, 1941, Serial No. 405,801

12 Claims. (Cl. 236—85)

This invention relates to regulators of the relay type generally used for the control of dampers, valves or rheostats either from pressure or temperature. Such regulators have a power motor either hydraulic or electric, a pilot control for controlling a source of power for operating the power motor, either valve or switch, and a device responsive to the condition to be regulated for operating the pilot control to thereby operate the power motor.

Various methods have heretofore been employed for stabilizing the operation of the power motor, the most common being what is generally referred to as a "follow up" system of control. With such regulators an equilibrium is attained at the expense of a drift in the condition under control, known as the operating range or operating band. Widening the operating band reduces the degree of over-correction, and thereby effects a more stable operation, but drift, due to variation in volume demand is increased. Conversely, narrowing the operating band reduces the drift but increases the degree of over-correction, all of which is objectionable.

My invention, generally stated, has for its object—

First, to provide high speed for sudden changes from one load condition, within a normal governing range, to another load condition outside the normal governing range; second, to eliminate drift to variations in volume demand and third, to provide an efficient stabilizing means within the normal governing range. Other novel features and combinations tending to increase the general efficiency of the stabilizing means are set forth in the appended claims.

To accomplish these objects applicant provides a governing or stabilized control range of approximately 25% of the total range of the regulators, beyond which the regulator has no damping restraint until stopped by a reversal of the condition under control.

Ordinarily the fluctuations of the volume demand is not so wide as to require more than 25% of the total operating travel of the regulator, but there remains the possibility of a sudden swing from full load to no load and in such a case speed retarding action is objectionable. It is just as important to guard against the pressure or temperature getting away from the control of the regulator, because of slow response, as it is to guard against over-shooting, because of a lack of damping action. From this it will be seen that applicant's regulator should have high speed when speed was required but otherwise to have

an effective damping action within the normal governing range. This result has been accomplished by using a step cam having a limited degree of operation, as compared with the total operating range of the regulators, and to provide a slip clutch arrangement for this cam for movements beyond the ordinary governing range, which permits the cam to be moved into the new regulating position and thereby become effective

10 in any position of the regulator.

The second object of my invention is in the use of what is known as a "fluid coupling" interconnecting the step-cam with the pilot control. In the fluid coupling method of stabilizing control, whenever equilibrium is attained, the condition under control; as an example, pressure or temperature, will always be the same; that is to say, there will be no drift of a rising and falling scale as in the "follow up" system of control.

15 20 The trouble is that, unless the coupling is effective in its operation, equilibrium will never be attained and as a result the regulator will set up a continuous hunting action. Therefore, the third object of my invention is a novel stabilizing arrangement which has been found to be more effective than those heretofore in use. The ordinary fluid coupling comprises a cylinder having a piston therein and involves a stuffing box through which the piston rod extends. The ob-

25 30 35 40 The objection to such an arrangement is that the friction of the stuffing box impairs the efficiency of the coupling, furthermore, there being no excess fluid within the cylinder, a small amount of leak past the stuffing box allows air to enter the cylinder, which further impairs the efficiency of the coupling.

The novel feature of applicant's fluid coupling comprises an oscillating casing with an oscillating plunger therein, each having a common axis of rotation; with the casing adapted to hold oil in excess of that required for the plunger; the arrangement being such as not to require a stuffing box; and in other details, constituting an efficient connecting link between the operating cam and the pilot control.

45 Referring to the drawings,

Fig. 1 shows my invention as applicable to an electric motor operated regulator of the type 50 shown in my Patent No. 1,567,995 of December 29, 1925.

Fig. 2 shows the elements of the invention as disconnected from the regulator of Fig. 1.

Fig. 3 shows my invention as applicable to a 55 hydraulically operated type of regulator of the

class shown in my Patent No. 1,597,203 of August 24, 1926.

Fig. 4 shows the arrangement which constitutes my invention as disconnected from the regulator of Fig. 3.

Fig. 5 shows a temperature control element which may be substituted for pressure control.

I will describe my invention as operating to control pressure although it has been found equally efficient as a temperature control when equipped with a thermostatic element as shown in Fig. 5, which can be applied to either the electric or hydraulic types of regulators.

Referring to Fig. 1 an electrically reversible motor 1 drives a train of speed reduction gearing comprising worm 2, worm gear 3, pinion 4 and spur gear 5. Spur gear 5 is mounted on shaft 6 the opposite end from that shown extends out on the back side of the gear housing and constitutes the power take-off drive for operating valves, dampers, rheostats or other like devices whose operation effects the pressure setting of the regulator, acting through pipe connection 7. The pressure sensitive device 8, which operates reversing switch 9, can be of any suitable construction; a preferred arrangement would be as shown in my Patent No. 1,567,995 of December 29, 1925.

The switch operating lever 10 operates the switch casing 11 which is of insulating plastic material and supports contact brushes 18, 19 and 19'. A circuit controlling plunger is comprised of part 12 for closing a circuit between 18 and either 19 or 19', and insulating end parts 13 and 14 are operated from a cam 15 which is driven from shaft 6 by means of a friction plate 16. The motion imparted by the cam is transmitted through the fluid coupling 17, to govern the pilot switch 9.

This novel arrangement of fluid coupling together with the step cam arrangement constitutes applicant's invention, the operation of which is described in detail in connection with Fig. 2.

Referring to Fig. 2, I will now describe the action of the fluid coupling 17. This coupling comprises a casing 21 suspended from shaft 27 which in turn is supported by bracket 20 attached to the gear housing. Mounted on shaft 27 within the casing is arm 26 having a screw stud 24 at its lower end which supports a ball 25 intended to transmit angular motion to dash-pot plungers 23 and 23'. Shaft 27 is rocked by means of bell crank 28 having a roll 29 at the upper end which contacts with cam 15. The arrangement is such that the action of the cam 15 oscillates the plunger 23 and 23' within the end cylinder 22 and 22' the return motion being effected by spring 30. The casing 21 and cylinders 22 and 22' are supplied with light weight transil oil of a sufficient amount to cover the plunger 23 and 23'. Casing 21 has an arm 31 which operates contacting plunger 12 by means of connection 32 and 33.

In the operation of this fluid coupling the centering springs 34 and 34' shown in Fig. 1 hold the casing in a centered position and consequently the switch 9 in a neutral position.

Electrical connections indicated by A and B extend to limit switches (not shown) which remain closed until the limit of operation of the regulator has been reached in either of two directions.

On increase in pressure the end of lever 10 connected to the control switch casing moves

downward making contact between 18 and 19 which operates motor 1 in a direction to turn cam 15 counterclockwise as indicated by the arrow. This movement through the action of the plungers 23 and 23' causes the body of the fluid coupling 17 to be rocked in a clockwise direction forcing contacting cylinder 12 downward and breaking the circuit. The operation of the controlling apparatus, valve, damper or rheostat, as the case may be, causes the pressure to be reduced and the lever 10 will consequently move upward to its original position at the same time the springs 34 and 34' act to center the fluid coupling into its normal or equilibrium position, as a result the pressure remains the same as at the beginning of the cycle of operation although the volume flow has been decreased. On a decrease in pressure, as on increase in volume demand, the lever 10 moves upward moving the switch casing 11 upward which causes contact to be made between 18 and 19' which operates the motor 1 in the opposite direction and the cam 15 in a clockwise direction. This operation causes the roll 29 to assume a lower step position which allows spring 30 to force plungers 23 and 23' to the right thus rocking casing 21 to raise arm 31 and return the switch contacting cylinder 12 to its neutral position. The pressure sensitive device and lever 10 have now been returned to their original position through the increase volume flow due to a wider open valve or like device.

The advantage of the fluid coupling thus described is in the specific arrangement of parts which give it a maximum of effectiveness in maintaining an equilibrium condition of the system for all volume demands.

In cases where time lag between change and correction response is excessive then a heavier oil can be used in the dashpot chamber thus making the coupling more effective in avoiding an over-correction due to the transportation lag of the system.

I will now explain the operation in which the slip-cam performs an important function. Assuming a sudden demand on the system outside of the normal load fluctuations or, assuming that the normal demand is close to the maximum capacity of the control valve or like device 40, and the volume flow is suddenly reduced we then require speed, free from damping action, in order that the regulator may reach a position corresponding to such sudden change in the least possible time. In such a case the cam is moved until the stud 35 contacts with either one or the opposite end of slot 36 after which the regulator operates without retarding effect into the new load position carrying with it the cam and again establishing stabilized control under the new load condition. There will be some over-travel before a reversal of operation takes place but this will be only what is required to return the control into its stabilized governing zone.

Applicant's invention is also applicable to regulators of the hydraulically operated type as shown in Fig. 3, such regulators have a pilot control valve 37 which controls a supply of fluid under pressure for operating a piston 38 within a cylinder 39 to control valve or damper as shown at 40. In principle the stabilizing means is similar to that of the electric motor operated regulator but requires certain changes in construction details to adapt it to regulators of the hydraulic class which will be explained in connection with Fig. 4, reference also being had to Fig. 3.

Diaphragm 41 constitutes a pressure sensitive device adapted to be actuated by the pressure to be regulated. Variation of pressure acting on diaphragm 41 is transmitted by means of pressure cap 42 to lever 43, the total pressure on the diaphragm being counteracted by spring 44. A floating arm 45 is mounted on lever 43 and serves the purpose of a joint control of the pilot valve 37 from the diaphragm and from the step-cam 46. Step-cam 46 is mounted on operating bar 47 which is attached to the piston rod at 48 and operated by piston 38. Step-cam 46 is driven by operating bar 47 by frictional contact therewith in any approved manner. A preferred arrangement is to split the ends and clamp it to this bar by means of threaded screws 60 and 60'. Spring 49 answers the purpose of holding roll 29 in contact with the stepped cam 46. Arm 31 has a link 50 which completes the connection between cam 46 and control valve arm 45. The fluid coupling 17 is rotatively supported from bracket 51 which also acts to guide operating bar 47.

The pilot control valve 31 may be of any suitable construction, but preferably of the embodiment shown in by Patent No. 1,597,203 already referred to. The inlet for fluid under pressure is shown at 56 and the exhaust at 57. A port 58 leads to the bottom of the motor piston 38 and a port 59 leads to the top of motor cylinder 39 above the piston. A preferred type of pilot valve has similar mode of operation as a preferred type of pilot switch for electric regulators, namely, that it has a neutral position in which it is not effective in operating the piston 38 and effective positions on opposite sides of the neutral position for operating the piston in either one or the opposite direction.

In the operation of the hydraulic type of regulator an increase in pressure acting on diaphragm 41 through pipe connection 52 causes right hand end of lever 43 to be raised, thereby actuating pilot valve stem 62 by means of yoke 63 admitting fluid under pressure under piston 38, at the same time opening exhaust port and venting the upper end of the cylinder to atmosphere thus forcing the piston upward to close damper or valve 40. It will be understood that if it were not for the stabilizing means the dampers or valve, as the case might be, would be fully closed, or closed to a point where the pressure acting on diaphragm 41 was reversed which would mean, due to time lag of the system, an over-correction and consequent hunting action. Applicant's stabilizing means acts to check the movement of the piston 38 before reaching a point of over-correction and this is accomplished in the following manner. As operating bar 47 moves upward with the movement of piston 38 it carries with it the step-cam 46 thus forcing arm 28 to the right and dash-pot pistons 23 and 23' to the left, moving casing 21 in the same direction pulling down on arm 50 and adjusting floating lever 45 to return the pilot control valve to its neutral position and checking the operation of the piston 38. This operation means that there will be a reduction of pressure acting on diaphragm 41, as soon as the transportation lag of the system is completed, which normally would cause a reversal of operation. Simultaneously with the reduction in pressure centering springs 34 and 34' move the casing 21 in the opposite direction, which raises connecting link 50 and valve stem 62 thus compensating for the reduction of pressure on diaphragm 41 and 75

in this way holding the pilot control valve to its neutral or non-effective position. On a reduction of pressure on diaphragm 41 the reverse operation takes place and the valve, damper, or like device is operated step by step in either of two directions without over-correction or hunting action, within the normal governing range. Now assuming that a sudden change in volume demand took place, which caused the regulator 10 to assume a position outside the normal pressure fluctuating range, then either one or the other end of the cam 46 which is frictionally driven from bar 47 will contact with the right hand side of bracket 51, after which the piston 15 38 can operate at full speed, without any damping action from the fluid coupling, until a reversal in pressure takes place to drive the regulator back into its control zone, after which it can again operate under stabilized control but 20 under a new volume load condition.

Should the regulator be required for temperature control then all that is necessary is to substitute thermostatic element as shown in Fig. 5 for that of the pressure responsive diaphragm

25 41 shown in both the electric and hydraulic types of regulators. A thermostatic element consisting of a flexible metal bellows 53, bulb 54, capillary tube 55, containing ether or other volatile liquid suitable for the purpose, although other forms of thermostats may be used without departing from the scope of the invention.

It will be seen by those skilled in the art to which my invention belongs that I have devised novel and useful means for stabilizing regulators 35 of the relay type whereby the speed of the regulator is controlled within the normal operating range to maintain the conditions to be regulated at a uniform value and whereby the regulator has uncontrolled speed outside of the normal operating range.

In accordance with the provisions of the rules of practice of the Patent Office, I have described the principle of operation of my invention, together with the apparatus which I now consider 45 to represent a preferred embodiment thereof; but I desire to have it understood that the apparatus shown is only illustrative and is capable of various modifications and that only such limitations shall be imposed as are indicated in the appended claims.

I claim:

1. In a regulator, the combination with a device 55 adapted to control variables of a fluid pressure system to be regulated, of a motor for operating said device, a pilot control element adapted to control a source of power to operate said motor, an element responsive to said variables for operating the pilot control element, a fluid coupling operated from the power motor, in any position 60 thereof co-operating with the responsive device in governing the pilot control element, said coupling comprising two cooperating elements with resilient means for centering said coupling at a neutral position and having an effective degree of 65 operation relatively limited as compared to the degree of operation of said motor, and a slip clutch interposed between the motor and said coupling.

2. In a regulator, the combination with a device 70 adapted to control variables of a pressure system to be regulated, of a motor for operating said device, a pilot control element adapted to control a source of power to operate said motor, a pressure element responsive to a variable of the system for operating the pilot control element, me-

chanical coupling means operated by the motor and co-operating with the responsive element for governing the operation of the pilot control element, said means comprising two oscillating elements each being rotatably mounted on a common axis and having resilient means for normally centering said coupling in a position corresponding to the centered position of the pilot control element, and a slip-clutch interposed between the motor and said coupling whereby the motor may be operated to a degree in excess of its normal governing range.

3. In apparatus for the regulation of a condition comprising, in combination, a motor adapted to be actuated by auxiliary power and means operated thereby for controlling the condition of the system, of a pilot control element adapted to control auxiliary power to actuate said motor, an element responsive to variations in the condition of the system for operating the pilot control element, a multiple step cam operated by said motor, effective in any position thereof, and having a governing degree of operation relatively limited as compared with the effective degree of operation of said motor, means operated by said cam, co-operating with said responsive element and said pilot control element, adapted to govern the power motor while operating within the normal fluctuating range, and means to permit uncontrolled operation of the power motor outside of said normal fluctuating range, said last means including a slip clutch interposed between the motor and said cam.

4. In a regulator, the combination with a device adapted to control variables in a system to be regulated, of a motor for operating said device, a pilot control element for controlling a source of power to operate said motor, an element responsive to said variables for operating said pilot control element, a step-cam operated by said motor, effective in any position thereof, and movable within the normal fluctuations of said system only, a dash-pot interconnecting said cam with said pilot control element, to thereby adjust said pilot control element to govern the operation of the power motor, while operating within the normal fluctuating range, said dash-pot comprising two cooperating elements with resilient means for centering the same at a neutral position, and a slip-clutch interposed between the motor and said cam permitting uncontrolled operation of the power motor outside of said normal fluctuation range.

5. In a regulator, the combination with a device for controlling variables of a system to be regulated, of a motor for operating said device, a pilot control element adapted to control a source of auxiliary power to operate said motor, an element responsive to variations in the condition of the system for operating the pilot control element, a step-cam operated by said motor, effective in any position thereof, and having governing degree of operation relatively limited as compared with effective degree of operation of said motor, means operated by said cam, co-operating with the responsive element, adapted to govern the pilot control element, said means comprising an oil dash-pot consisting of two reciprocating elements, one of said elements being operated by said cam, and resilient means for normally maintaining said elements in a centered or neutral position and a slip clutch interposed between the motor and said cam.

6. In a regulator, the combination with a device adapted to control variables of a system to be

regulated, of a motor for operating said device, a pilot control element adapted to control a source of power to operate said motor, an element responsive to variations in the condition to be regulated for operating the pilot control element, a cam operated by said motor, effective in any position thereof, and having a governing degree of operation relatively limited as compared with the effective degree of operation of said motor, means operated by said cam, co-operating with the responsive element, comprising two oscillating elements each having a common axis, one of said elements includes a dash-pot plunger operated from said cam, the other element comprises the casing for the first named element, means connecting the casing with the pilot control, and resilient means for normally maintaining the casing in a centered or neutral position in relation to the pilot control element and a slip clutch interposed between the motor and said cam.

7. In a regulator having a power motor and a pilot control, a device responsive to the condition to be regulated for operating the pilot control, a fluid actuated coupling operated from the power motor and co-operating with responsive device, for governing the operation of the pilot control, said coupling comprising two oscillating co-operating elements suspended from a stationary support and rotatably mounted on a common axis, one of said elements includes a double ended spool plunger, the other element comprises the casing for the first named element, means for operating said plunger from the power motor to thereby actuate the casing, mechanical means operatively connecting the casing with the pilot control and resilient means for normally centering said casing in a position corresponding to the centered position of the pilot control.

8. In a pressure regulator, comprising, in combination, means to control the pressure, a fluid pressure motor for actuating the pressure controlling means, a pilot valve having a neutral position and two effective positions, adapted to control a source of fluid under pressure, for operating said motor in either one or the opposite direction, a pressure responsive device for operating the pilot valve, a fluid coupling operated by the motor and co-operating with the pressure responsive device for governing the operation of the pilot valve, said coupling comprising two oscillating co-operating elements rotatably mounted on an axis common to both elements, and having resilient means for normally centering one of said elements in a neutral position corresponding to the neutral position of said pilot valve, and a slip clutch interposed between the motor and said coupling, whereby the motor may be operated to a degree in excess of the degree of operation of the fluid coupling.

9. In a temperature control regulator, comprising in combination, means to control the temperature, a reversible motor for actuating the temperature controlling means, a control element having a neutral position and two effective positions, adapted to control a source of power to operate said motor in either one or the opposite direction, an element responsive to variations in temperature adapted to actuate the control element to either one or the other of its effective positions, mechanical means including a fluid coupling operated by the motor and co-operating with the temperature responsive element, adapted to govern the operation of the control element, said coupling comprising two oscillating co-operating elements rotatably mounted on a common

axis and having springs for centering one of said elements in a neutral position corresponding to the neutral position of said control element, and a slip clutch interposed between the motor and said coupling whereby the motor may be operated in excess of the degree of operation of the fluid coupling.

10. In a regulator, the combination with a device adapted to control variables of a pressure system to be regulated, of a motor for operating said device, a pilot control element having a neutral position and two effective positions adapted to control a source of power to operate said motor in either one or the opposite directions, a pressure responsive element for operating the pilot control element, mechanical means operated by the motor and co-operating with the pressure responsive device in governing the pilot control element, said means including a cam, a friction clutch, and a fluid coupling, said coupling comprising two cooperating elements and having a resilient means for normally centering one of said elements in a neutral position corresponding to the neutral position of the pilot control, the several elements cooperating to govern the motor to maintain substantially constant pressure within the operating range of the cam and permitting control of the motor from the pressure device only outside said range.

11. In a regulator having a power motor and a pilot control, a device responsive a condition

to be regulated for operating the pilot control, a fluid actuated coupling operated from the power motor and mechanically co-operating with the responsive device in governing the operation of the pilot control, said coupling comprising two co-operating elements depending from a stationary support and rotatively mounted on a common axis, means operated by the power motor for operating one of said elements to thereby operate the other element to govern the operation of the pilot control, and resilient means for normally centering the last named element in relation to a neutral position of the pilot control.

12. In a regulator having a power motor and a pilot control, a device responsive to the condition to be regulated for operating the pilot control, a fluid coupling interposed between the motor and pilot control, said coupling comprising a casing depending from a stationary support and rotatably mounted thereon, said casing having end caps defining dash pot cylinders for supporting a double ended spool plunger, resilient means for normally centering said casing in an approximately vertical position, means to operate said plunger from said motor to thereby operate said casing to either one or the opposite side of its vertical position, and means operated by the casing co-operating with the responsive element to govern the pilot control.

JAMES L. KIMBALL.
